UNITED STATES PATENT OFFICE

JAMES W. HIGHLEYMAN, OF OMAHA, NEBRASKA

LOCOMOTIVE CROSSHEAD

Application filed April 22, 1929. Serial No. 357,260.

My invention relates to crossheads and particularly to those of the type used in steam locomotives.

One object of my invention is to provide a crosshead with shoes or gibs which are readily adjustable to compensate for wear without their removal from the crosshead.

Another object is to provide a gib fastening structure which eliminates the use of transverse bolts, thereby greatly facilitating repair and replacement of parts of locomotives in service.

A further object is to provide a crosshead in which the gibs are securely locked in a solid crosshead body with a single removable member for holding each gib in position.

Still another object is to provide a durable crosshead structure which can be produced by a simple alteration of crossheads now in use.

Other objects will appear from the following specification when read in conjunction with the accompanying drawings in which

Figure 1 is a perspective view of the body of a crosshead embodying my invention, the gibs or shoes being removed;

Fig. 2 is a longitudinal section through the crosshead body shown in Fig. 1;

Fig. 3 is a perspective view of a gib used in the crosshead;

Fig. 4 is a perspective view of a block used for holding the gibs in place;

Fig. 5 is a perspective view of an adjusting liner or shim;

Fig. 6 is a sectional view of an assembled crosshead, the section being taken on line VI—VI of Fig. 7; and

Fig. 7 is a sectional view of the assembled crosshead, the section being taken on line VII—VII of Fig. 6.

Referring to Fig. 1 the reference character 8 designates the body of a crosshead commonly known as the alligator or butterfly type. This body carries an integral extension 9 for the reception of the usual piston rod and a transverse opening 10 for the wrist pin. The body 8 has the usual integral side plates or wings 11, but these wings are connected at their rear ends by solid integral connecting blocks 12 which form rear end closures for

slots 13 which are cut in the top and bottom of the crosshead. The front faces of blocks 12 are here shown as being cut away to form an undercut inclined surface 14 containing drilled openings 14a.

The slots 13 in block 8 are adapted to receive and hold in position gibs 16 which cooperate with suitable crosshead guides. As here shown, each gib 16 has an integral projection 15 extending from its flat surface and these projections are dove-tailed in cross section forming inclined faces 18 which are arranged to contact with and fit against the undercut surfaces 14 of blocks 12. The projections 15 contain longitudinal grooves 17 in their horizontal faces and extending parallel to the flat surface of the gib. When a gib 16 is placed in position with its projection 15 entering a slot 13 of the crosshead, one of the inclined faces of this projection engages the undercut face 14 of block 12.

For the purpose of closing the open end of slot 13 and securing the gib rigidly in position, I provide closure blocks 19 having laterally extending tongues 20 which enter and engage with grooves 21 in the wings 11. The inner end of each block 19 has an inclined face 22 cut at the same angle as the faces 18 on projection 15. When the block is placed in the outer end of slot 13 with its tongues 20 engaging grooves 21, the inclined face 22 engages and closely fits against the inclined surface 18 on projection 15. The block 19 contains longitudinal drilled openings 20a which are adapted, when the block is inserted in slot 13, to be in accurate alinement both with the grooves 17 in projections 15 and with the openings 14a in blocks 12. When the parts are in this position longitudinal bolts 23 are inserted from the rear ends of openings 14a through the grooves 17 in projections 15 and openings 20a in blocks 19, and are then tightened into position by means of nuts 23a. It will be seen that by a sufficient tightening of these bolts 23 the gibs can be securely fastened in place without the necessity of any complicated adjustments. Obviously tap screws or equivalent means may be substituted for bolts 23 by threading the

openings 14a, thereby eliminating the use of nuts.

The gibs 16 are each provided with two side wings 24 which cooperate with the usual

5 crosshead guides and carry spaced Babbitt liners 25 of conventional type. As shown in Fig. 6 two liners or shims 26 are associated with each of the gibs 16. These liners are of the form shown in Fig. 5 and have a long 10 flat portion 27 adapted to contact with the upper face of the crosshead block, and a vertical portion 28 containing openings 29 through which the bolts 23 pass. The purpose of these liners is to afford a simple means 15 for taking up wear in the crosshead without removing the crosshead from the engine. Whenever the gib becomes worn away so as to allow too much play between the gibs and their associated guides, additional or thicker 20 shims 26 can be placed into position by simply removing the two longitudinal bolts which pass through each of these shims. It will be noted that these shims are entirely outside of the slots 13 so as to be conveniently accessible.

25 The advantages of the structure just described are numerous as will be evident to those skilled in the art to which this invention relates. The absence of bolts extending transversely through the crosshead not only improves the looks of the mechanism and makes it easier to clean and polish, but it enables 30 adjustments to be made without bringing the crosshead to a particular position before the gib fastening bolts can be removed. Furthermore, 35 adjustments can be made without removing the crosshead and hence, without going to the trouble of removing the wrist pin from the crosshead. This invention is applicable not only to new crossheads, but it can be readily applied to those already in use by welding, pinning, or otherwise securing blocks in the rear ends 40 of the gib-receiving slots, and then cutting grooves in the front ends of these slots to receive the fastening blocks.

45 My invention produces a crosshead which is more durable than those known heretofore, is simple to adjust for maintaining proper clearance between guides and gibs, and assures a permanent fit of the crosshead wrist pin in the crosshead. It also materially reduces the cost of upkeep and entirely eliminates the numerous roundhouse delays which have heretofore been necessary for adjusting 55 crosshead guides to take up wear.

Although I have herein shown and described only one form of crosshead embodying my invention, it will be obvious that various changes and modifications may be made 60 in the details thereof within the scope of the appended claims, without departing from the spirit and scope of the invention.

What is claimed is:

65 1. A crosshead comprising a block containing gib-supporting slots open at one end

only, gibs each having a portion fitted in one of said slots, and removable blocks one being secured in each of said slots for closing the open ends of the slots and holding the gibs in position.

70 2. A crosshead comprising a block having gib-supporting slots open at one end only, a gib in each slot and having an inclined face cooperating with an inclined face at the closed end of the slot, a removable block secured in the open end of each slot and engaging an inclined surface on its gib, and means extending longitudinally of the crosshead for securing the removable blocks and gibs to the crosshead block.

75 3. A crosshead comprising a block slotted on two faces, said slots being permanently closed at one end, removable means for closing the other end of each of said slots, and gibs one associated with each of said slots 80 and each having a single projection adapted to enter one of said slots and to be held therein by said removable means.

85 4. The combination with a crosshead having slots in its guide-adjoining sides, said slots being closed at one end and having an undercut face on said end only, of gibs one in each of said slots and having an inclined portion adapted to engage said undercut face, removable blocks one for closing each of said 90 slots and having an inclined face for cooperation with an inclined portion of a gib, and means extending longitudinally of the crosshead for securing the blocks in the slots 95 and locking the gibs against displacement.

100 5. A crosshead comprising a block having gib-receiving slots on its guide-adjoining sides, means for permanently closing one end of each of said slots, each of said means having an undercut face, gibs one in each of said slots and each having an inclined surface for contacting with said undercut face, closure blocks one adapted to fit in the open end of each of said slots and each having an inclined surface for engagement with an inclined surface on the associated gib, means extending parallel to the guides for holding the gibs in position, and a plurality of removable liners between the gibs and the outside surfaces of the crosshead.

115 6. A crosshead comprising a block having gib-receiving slots on its guide-adjoining sides, means for permanently closing one end of each of said slots, each of said means having an undercut face, gibs one in each of said slots and each having an inclined surface for contacting with said undercut face, closure blocks one adapted to fit in the open end of each of said slots and having an inclined surface for engagement with an inclined surface on the associated gib, means extending parallel to the guides for holding the gibs in position, and removable means outside of said slots for varying the distance between the gibs and the crosshead.

7. A crosshead comprising a block having gib-receiving slots on its guide-adjoining sides, each slot being permanently closed at one end and having a removable block for closing the other end, to form a recess dove-tailed in cross section, a gib having a dove-tailed projection adapted to fit in each of said recesses, means extending longitudinally of the crosshead for securing the gibs in said recesses, and a plurality of removable liners separating the guide-adjoining faces of the crosshead from the adjoining flat faces of the gibs.
8. A crosshead comprising a block having gib-supporting slots open at one end only, a gib in each slot and having an inclined face cooperating with an inclined face at the closed end of the slot, a removable block secured in the open end of each slot and having an inclined surface engaging an inclined surface on each gib, and means for securing the removable blocks and gibs to the crosshead block.

In testimony whereof I have signed my name to this specification.

JAMES W. HIGHLEYMAN.
